ANTENNA

Willoughby M. Cady, Cambridge, Mass., assignor,
by mesne assignments, to the United States
of America as represented by the Secretary of
War

Application December 29, 1944, Serial No. 570,413

6 Claims. (Cl. 250—33.65)

1

This invention relates to directional antennas which are particularly applicable to radio direction-finding or object-location systems operating in the ultra high frequency region, or higher.

It is the object of this invention to provide a directional antenna so constructed and arranged that the scanning pattern which is produced by the antenna can be readily changed merely by varying the rotative speeds of certain elements.

For a better understanding of the invention, together with other and further objects thereof, reference is had to the following description taken in connection with the accompanying drawing, wherein like parts are indicated by like reference numerals.

Fig. 1 is a sectional view of a preferred embodiment of the invention;

Fig. 2 is a diagrammatic view of the antenna, showing the components in different relative positions as compared with Fig. 1; and

Figs. 3, 4 and 5 are, respectively, diagrammatic views of three different scanning patterns that can be obtained by means of the invention.

In Fig. 1 there is shown an antenna comprising a wave transducer, such as a dipole 10, situated substantially in the focal plane of a paraboloidal reflector 12 but displaced from the axis PA thereof. The reflector is mounted on a hollow shaft 14 which is adapted to be rotated by means such as shown schematically in Fig. 1 wherein a scanning motor 11 drives the shaft 14 through the medium of bevel gears 13 and 15. The axis of rotation, or spin axis of the paraboloid, indicated by the solid line SA, is disposed at an angle with respect to the paraboloid axis PA.

Dipole 10 is mounted on a support 16 fastened to or integral with a rotatable shaft 18 extending through and coaxial with the shaft 14. The dipole support 16 and shaft 18 may form a part of the antenna feed, the portion 16 extending at an angle with respect to the spin axis SA. Shafts 14 and 18 are adapted to be simultaneously rotated in opposite or in the same direction, at the same or relatively different speeds. Any desired means for adjusting the relative speeds and direction of rotation of either shaft 14 or 18, or both, may be utilized. For purposes of illustration, shaft 14 is shown as being driven by scanning motor 11 through the medium of bevel gears 13 and 15, and shaft 18 is shown as being driven by said scanning motor through the medium of bevel gears 17 and 19. Reversing mechanism 20 and change speed gear 21 are illustrated as providing means for respectively

determining the direction of rotation and/or the speed of shaft 18. Although means to adjust the speed and/or direction of rotation of only shaft 18 is shown, it is to be understood that said means may also be applied to change the speed and/or direction of rotation of shaft 14, or of both shafts.

In the example shown in Fig. 1, it will be assumed that the spin axis SA is at an angle θ with respect to the paraboloid axis PA, and the support 16 is at an angle 2θ with respect to said spin axis. It will also be assumed that the dipole and reflector are rotating in opposite directions at the same speed. With the positions of the elements as shown, if specular reflection is assumed, the direction of maximum radiation RA will be at an angle of 3θ from the parabolic axis PA, or 4θ with respect to the spin axis SA. This angle is the maximum angle of reflection with respect to the spin axis. One-half cycle of rotation later, the relationship of the antenna elements will be reversed, so that the maximum angle of reflection will be at an angle 4θ from the spin axis but in the opposite direction.

Fig. 2 shows the conditions existing one-quarter cycle from the instant represented in Fig. 1. The drawing is taken through a plane at right angles to the plane shown in Fig. 1. Here the angular deflections of the respective axes relative to that of the spinner axis are the same as shown in Fig. 1, but the deflections are in the same sense. From this diagram, it can be seen that the radiated energy will be deflected an angle θ with respect to the parabolic axis. This places the axis of radiation along the spinner axis so that the radiation is still in the same plane as that of Fig. 1. For intermediate positions between the two limits shown in Fig. 1 and Fig. 2, it will be found that the radiation is always in one plane, as indicated in Fig. 3. Such an arrangement is particularly useful for limited sector scanning.

If the two rotation rates are slightly different, the rosette pattern shown in Fig. 4 will result. In this case, the speed of rotation of the reflector 12 is either slightly faster or slower than the rotation of the feed 16. A conical scan may be afforded by maintaining one of the elements stationary so as to obtain a circular pattern. If on the other hand one of the elements, instead of being fixed, is rotated slowly with respect to the other rotating element, a pattern such as shown in Fig. 5 will be obtained. This consists of a circular conical scan pattern wherein the center of the circle travels along an arcuate path,

3

Further variation may be afforded by rotating the elements in the same direction at different speeds, thus making it possible to obtain a spiral scan, for example. It will be obvious that the angular and speed relations of the rotating elements can be varied to provide other scanning patterns.

While there has been described what is at present considered a preferred embodiment of the invention, it will be apparent to those skilled in the art that various changes and modifications may be made therein without departing from the spirit of the invention; hence it is not intended to limit the invention to the precise details disclosed herein but to cover all such changes and modifications as come within the purview of the appended claims.

I claim:

1. A directional antenna comprising a wave transducer and a paraboloidal reflector therefor, said transducer being situated in the vicinity of the focal plane of said reflector but displaced from the axis thereof, means to rotate said reflector in one direction about a second axis which is disposed at an angle with respect to the axis of the paraboloid, and means to revolve said transducer in an opposite direction about said second axis.
2. An antenna as set forth in claim 1, wherein the rate of rotation of said reflector is equal to the rate of revolution of said transducer.
3. An antenna as set forth in claim 1, wherein

5

the rate of rotation of said reflector is greater than the rate of revolution of said transducer.

4. An antenna as set forth in claim 1, wherein the rate of rotation of said reflector is less than the rate of revolution of said transducer.

5. A directional antenna comprising a wave transducer and a paraboloidal reflector therefor, said transducer being situated in the vicinity of the focal plane of said reflector but displaced from the axis thereof, means to rotate said reflector about a second axis which is disposed at an angle with respect to the axis of the paraboloid, and means to revolve said transducer relative to said reflector about said second axis.

6. A directional antenna comprising rotatable radiating and reflecting elements, and means adapted to rotate said elements in opposite directions during scanning.
